UNITED STATES PATENT OFFICE.

ROY WILKINS, OF SAN FRANCISCO, ALBERT T. CHURCH, OF OAKLAND, AND ARTHUR K. INGRAHAM, OF BERKELEY, CALIFORNIA; SAID CHURCH AND SAID INGRAHAM ASSIGNORS TO SAID WILKINS.

OIL-SWITCH-OPERATING DEVICE.

Application filed May 18, 1925. Serial No. 30,904.

This invention relates to switch operating mechanisms and particularly to an improved oil switch closing and opening mechanism operated by power means controlled from a distant point. It is well known that electric circuits of high potential and large current are controlled by switches in oil pots located in fireproof cells. The closing and opening mechanism for such switches is usually carried on the cell structure and is adapted in the switch closing and opening operations to vertically reciprocate the movable switch contacts. Heretofore the opening of the switches has quite commonly been performed by gravity and the closing thereof by an electric motor. It is desirable, however, that these switches should be positively opened and closed with a very quick action. It is accordingly the primary object of our invention to provide an improved switch operating mechanism controllable from a distant point and adapted by a minimum of power to effect the rapid closing and opening of such switches.

It is a further object of our invention to provide a switch operating mechanism of this type wherein a pair of springs are automatically wound up by a motor, are locked in such condition in a manner also locking the switches in either the closed or open position, and operated by trip mechanism controlled from a distant point to close and open the switches by a quick and powerful action. It will be understood that such a mechanism requires the use of only a very small electric motor which operates automatically to store up energy in the springs and which energy reacts in a relatively short period of time to perform its switch-moving function.

With the above and other objects in view, as will hereinafter appear, our invention consists in the features of construction and operation set forth in the following specification and illustrated in the accompanying drawings. In such drawings, annexed hereto and forming a part of this specification, we have shown certain specific embodiments of our invention, but it will be understood that the invention can be otherwise embodied, and that the drawings are not to be construed as defining or limiting the scope of the invention, the claims appended to this

specification being relied upon for that purpose.

Referring to the figures of the drawings, Fig. 1 is a plan view of our improved switch operating mechanism;

Fig. 2 is a side elevation thereof showing the parts in the wound-up position wherein the switch is open;

Fig. 3 is a like view showing one spring collapsed and wherein the switch is closed;

Fig. 4 is a like view showing both springs collapsed and wherein the switch is open;

Fig. 5 is an end view looking toward the right-hand end of Figs. 1 to 4;

Fig. 6 is a detail view illustrating how the switch operating mechanism may be connected to the switches to be closed and opened thereby;

Fig. 7 is a diagrammatic view of the wiring connections for controlling and operating the mechanism;

Fig. 8 is an enlarged plan view of a controlling switch shown in Fig. 1;

Fig. 9 is a sectional view on line 9—9 therethrough.

Referring more specifically to the drawings by reference characters, 1 indicates the base on which our improved switch-operating mechanism is mounted. Rock shafts 2 and 3 are respectively mounted in uprights 4 and 5 at the ends of the base. The shaft 2 carries an arm 6 at its rear end which is adapted to be connected to the switch or switches to be operated.

In Fig. 6 we have illustrated three switches, each mounted in an oil pot 7. Each of these switches comprises two stationary contacts 8 and two co-operating movable contacts 9 carried on a vertically extending rod 10. Bell cranks 11 connect the rods 10 to a horizontal rod 12 connected to the arm 6. It will be seen that rocking movement of the shaft 2 in one direction will close the switches and movement thereof in the opposite direction will open the switches.

Lever arms 13 and 14 are mounted respectively on the forward ends of the shafts 2 and 3. A bell crank lever 15 is pivoted to the upper end of lever 14 at 16 in a manner forming a compound lever. A pair of tension springs 17 and 18 respectively connected at one end to adjustable screws 19

and 20 have their opposite ends connected to the lower arms 21 and 22 of levers 14 and 15. A link 23 connected to the upper end of lever 13 is pivotally connected to the free end of bell crank arm 24 at 25. A link 26 connected to pivot 25 has a slotted end 27 connected to a pivot pin 28 in the end of a crank 29 mounted for free rotation on a shaft 30. The shaft 30 is driven in the direction of the arrow by a motor 31 through a pinion 32 meshing with a gear 33 on the shaft. A lug 34 on the gear is adapted to engage and drive the crank 29.

When the parts are in the position shown in Fig. 4 it will be noted that rotation of the motor will operate through the gear 33 and lug 34 to move the parts to the position shown in Fig. 2, thereby stretching the springs 17 and 18. We provide a pair of toggle levers to hold the springs in this position. As best shown in Fig. 3, one such lever comprises a bar 35 pivoted to the base at 36 and pivotally connected to a link 37 at 38, the link 37 being pivoted to the lower arm of lever 13 at 39. The downward movement of the bar is limited by engaging an adjustable stop 40. This stop is adjusted to a position just permitting the toggle to pass its dead center, as illustrated in Figs. 2 and 4.

The toggle is adapted to be tripped or broken, to permit the spring to contract, by the following mechanism. A set screw 41 is mounted in the free end of the bar directly over the shorter end 42 of a lever pivoted at 43. The longer end 44 of this lever extends beneath a bar 45 connected to the core 46 of a solenoid 47. Energizing of the solenoid is adapted to draw the core 46 downwardly in a manner to raise the bar 35 upwardly beyond its dead center. A spring 48 is provided for thereafter raising the core upwardly to its normal position.

It will be understood that a like toggle mechanism including a bar 35' pivoted to the base at 36' and connected to the lower arm of lever 14 at 39' is provided on the other side of the shaft 30. Like tripping means, including a solenoid 47', is also provided for this mechanism.

The motor circuit is automatically closed to rewind the device to its operative position, the solenoids 47 and 47' are controlled from a distant point and the position of the device indicated at such point by mechanism now to be described. This mechanism is shown diagrammatically in Fig. 7.

Two like switch units 49 and 50 are mounted on a plate 51 carried by the uprights 4 and 5. A block 52 of insulating material is slidably mounted in each unit and each block has a pair of horizontal arms carrying two contact elements 53 and 54 therein. The block 52 in unit 49 in one

position closes the contacts *a* and *b* and in the other position closes contacts *c* and *d*. The blocks 52' in unit 50 in one position closes contacts *e* and *f* and in the other position closes contacts *g* and *h*.

The contact block 52' is connected by a rod 55 to a pin 56 in the lever 13 in a manner to slide the block to its two positions when the lever moves to its two positions. When the lever is in the position of Fig. 2 the contacts *d* and *f* are closed and when in the position of Fig. 3 the contacts *g* and *h* are closed.

The block 52 is connected to a rod 57 slidably mounted in a bracket 58. The other end of the rod is carried by a pin 59 on the lever 14. When the lever is in the position of Fig. 4 the block is in the right-hand position and contacts *a* and *b* are closed. In such position a toothed latch 60 pivoted at 61 engages a lug 62 on the rod in a manner preventing movement of the rod to the left. When the lever moves to the position of Fig. 2 a spring 63 on the rod is pressed against a shoulder 64 thereon. The spring is held thus compressed until a screw-head 65 on the gear 33 engages against another arm 66 and against the latches 60. The spring thereupon moves the rod and block to the left and closes contacts *c* and *d*. A small buffer spring 67 is provided on the rod 57 at the opposite side of the pin 59.

In Fig. 7 is diagrammatically illustrated the electrical connections for controlling and operating the mechanism. Two positive and negative terminals are indicated respectively by P and N. The contact switches for the solenoids 47 and 47' are indicated by 68 and 68'. G is a green electric bulb which is lighted when the switches 9 are open and the springs 17 and 18 are expanded to their operative position as indicated at Fig. 2. R is a red electric bulb which is lighted when the switches 9 are closed.

The operation of the device is substantially as follows:

It is assumed that the parts are in the wound-up position, as illustrated in Figs. 1 and 2, wherein the switches 9 are in the open position (Fig. 6). In such position of the parts, the contacts *c*, *b*, *e*, and *f* are closed. This position is indicated by the green light G which is lighted by a circuit PGfcN (Fig. 7).

To close the switches 9, the operator closes the switch 68, whereupon the following circuit is established, N, 68, 47, *eb*, P, thus energizing the solenoid 47 and breaking the locking toggle at 38. The spring 18 thereupon reacts to move the parts from the position shown in Fig. 2 to the position shown in Fig. 3. In this movement the crank 15 rotates on its pivot 16 and through the link 23 rotates the lever 13 in a direction to close the switches 9. It will be noted that this

movement is a simple harmonic motion wherein the beginning of the switch-closing operation is relatively rapid and gradually diminishes to a final slow but powerful closing of the switches through the straightening out of the arm 24 and link 23. The switches 9 are thereby quickly and powerfully closed but are not closed with a slamming action. The crank 29 which is loose on the shaft 30 has rotated from the position of Fig. 2 to the position of Fig. 3 and the connecting rod 55 has moved the switch block 52' to the left to open contacts *e* and *f* and close contacts *g* and *h*. The position of the lever 14 has not been changed.

The opening of the contact *f* has broken the circuit of the green light *G* and the closing of the contact *h* has made a circuit *NRhP* through the red light *R*. This red light indicates that the switches 9 are closed.

To open the switches 9 the operator closes switch 68', whereupon the following circuit is established, *N*, 68', 47', *g*, *P*, thus energizing the solenoid 47' and breaking the locking toggle at 38'. The spring 17 thereupon reacts to move the parts from the position shown in Fig. 3 to the position shown in Fig. 4. In this movement the lever 14 rotates on its pivot 3 and moves the lever 13 in a direction to open the switches 9. In this operation the levers 13 and 14 have both been rotated to the right and moved the blocks 52 and 52' into position to make contacts *a*, *d*, *e*, and *f*.

The closing of the contacts *a* and *b* establishes a circuit *P*, *d*, motor, *a*, *N*, through the motor 31. The motor thereupon operates to rotate the gear 33 in the direction of the arrow. The lug 34 engages the crank 29 and rotates the same therewith. Movement of the switch block 52 with the lever 14 is prevented by the latch 60 engaging the lug 62. When the crank 29 passes its lowermost position, the springs 17 and 18 have been fully extended and locked in such position by the toggles at 38 and 38'. A screw-head 65 on the gear 33 thereafter engages an arm 66 and trips the latch 60. The spring 63 thereupon moves the block 52 to the left and breaks the contacts *a*, *d*. The motor then stops, leaving the parts in the fully wound-up position first described above and ready to repeat the same cycle of operations.

Having thus described our invention, what we claim and desire to secure by Letters Patent is:

1. A switch operating mechanism comprising the combination of a member adapted to be connected to a switch to close and open the same, spring means, operative connections between the spring means and the member, an electric motor, operative connections between the motor and spring means whereby operation of the motor places the spring means under strain during such oper-

ation, locking means for holding the spring means in such position, trip means for releasing the locking means in two stages, whereby upon the first tripping the spring means reacts to move the member to close the switch and thereafter upon the second tripping reacts to open the switch, and means for automatically closing the motor circuit to again place the spring means under strain when the switch is thus opened.

2. A switch operating mechanism comprising the combination of a member adapted to be connected to a switch to close and open the same, a pair of springs, operative connections between the springs and the member, an electric motor, operative connections between the motor and springs whereby operation of the motor places the springs under strain during such operation, locking means for holding the springs in such position, trip means for releasing the locking means in two stages, whereby upon the first tripping one spring reacts to move the member to close the switch and thereafter upon the second tripping the other spring reacts to open the switch, and means for automatically closing the motor circuit to again place the springs under strain when the switch is thus opened.

3. A switch operating mechanism comprising the combination of a member adapted to be connected to a switch to close and open the same, spring means, operative connections including a compound lever between the spring means and the member, an electric motor, operative connections between the motor and spring means whereby operation of the motor places the spring means under strain during such operation, locking means for holding the spring means in such position, trip means for releasing the locking means in two stages, whereby upon the first tripping the spring means reacts through the compound lever to move the member to close the switch and thereafter upon the second tripping reacts through the compound lever to open the switch, and means for automatically closing the motor circuit to again place the spring means under strain when the switch is thus opened.

4. A switch operating mechanism comprising the combination of a member adapted to be connected to a switch to close and open the same, a pivoted lever, means including one arm of a second pivoted lever pivoted to one arm of the first lever for connecting the same with the member, a pair of springs connected respectively to the other arms of the levers, an electric motor adapted to place the springs under strain, locking means for holding the springs in such position, trip means for releasing the locking means in two stages, whereby upon the first tripping one spring reacts through one lever to move the member to close the

4
switch and thereafter upon the second tripping the other spring reacts through other lever to open the switch, and means for automatically closing the motor circuit to again place the springs under strain when the switch is thus opened.

5. A switch operating mechanism comprising the combination of a member adapted to be connected to a switch to close and open the same, a pair of springs respectively adapted to close and open the switch, operative connections between the springs and the member whereby the reacting of the switch opening spring after the closing 15 spring has reacted tends to place the closing spring under strain, an electric motor adapted to place the springs under strain, locking means for holding the springs in such position, trip means for releasing the 20 locking means in two stages, whereby upon the first tripping one spring reacts to move the member to close the switch and thereafter upon the second tripping the other spring reacts to open the switch, the end 25 of such switch opening action being cushioned by the said straining action on the closing spring, and means for automatically closing the motor circuit to again place the springs under strain when the switch is 30 thus opened.

6. In combination, a switch, spring means, operative connections between the spring means and the switch, an electric motor, operative connections between the motor and 35 spring means whereby operation of the motor places the spring means under strain during such operation, locking means for holding the spring means in such position and the switch in either the open or closed 40 position which it occupies, trip means for releasing the locking means in two stages, whereby upon the first tripping the spring means reacts to close the switch and thereafter upon the second tripping reacts to open 45 the switch, and means for automatically closing the motor circuit to again place the spring means under strain when the switch is thus opened.

7. A switch-operating mechanism comprising the combination of a member

adapted to be connected to a switch to close and open the same, spring means, operative connections between the spring means and the member and including a pivoted lever arm having its inner end operatively connected to the member, an electric motor, operative connections between the motor and spring means whereby operation of the motor places the spring means under strain during such operation, locking means for holding the spring means in such position, trip means for releasing certain of the locking means whereupon the spring means reacts to open the switch, the operative connection of the lever arm being such that it opens the 65 switch by a simple harmonic motion wherein in the beginning of such operation is relatively rapid and gradually diminishes to a final slow but powerful operation, trip 70 means for releasing other of the locking means whereupon the spring means reacts to open the switch, and means for automatically closing the motor circuit to again place the spring means under strain.

8. A switch-operating mechanism comprising the combination of a member adapted to be connected to a switch to close the same, spring means, operative connections between the spring means and the member and including a pivoted lever arm having its free end operatively connected to the member, an electric motor, operative connections between the motor and spring means whereby operation of the motor places the spring means under strain during such operation, locking means for holding the spring means in such position, trip means for releasing the locking means whereupon the spring means reacts to close the switch, the operative connection of the lever arm being 80 such that it closes the switch by a simple harmonic motion wherein the beginning of such operation is relatively rapid and gradually diminishes to a final slow but powerful operation, and means for automatically 85 closing the motor circuit to again place the spring means under strain.
